Primary Examiner — Holly Baynham*Assistant Examiner* — Rhea Shields*(74) Attorney, Agent, or Firm* — Milton's IP/p.i.(57) **CLAIM**

The ornamental design for a beverage pod package, as shown and described.

DESCRIPTION

FIG. 1 is a perspective view of a beverage pod package, showing our new design;

FIG. 2 is a first side view of the design of FIG. 1.

FIG. 3 is a second side view of the design of FIG. 1.

FIG. 4 is a third side view of the design of FIG. 1.

FIG. 5 is a top view of the design of FIG. 1; and,

FIG. 6 is a bottom view of the design of FIG. 1.

In the drawings, the broken lines are for the purpose of illustrating environment only and form no part of the claimed design.
